UNITED STATES PATENT OFFICE

135,612

DESIGN FOR A GASOLINE STATION

Richard H. Fletcher, Jr., Bay City, Mich.

Application January 17, 1941, Serial No. 98,155

Term of patent 14 years

To all whom it may concern:

Be it known that I, Richard H. Fletcher, Jr., a citizen of the United States, residing at Bay City, in the county of Bay and State of Michigan, have invented a certain new, original, and ornamental Design for Gasoline Stations, of which the following is a specification, reference being had to the accompanying drawings, forming a part thereof.

In the drawings:

Fig. 1 is an isometric view of a gasoline station, showing my new design.

Fig. 2 is a rear elevational view thereof; and, Fig. 3 is an end elevational view.

Fig. 4 is a plan view.

What I claim is:

The ornamental design for a gasoline station, as shown.

RICHARD H. FLETCHER, JR.
